WATER SPRINKLER HOOP

Clement J. Da Prato, 6661 9th Ave. 95820, and Eddie Da Prato, Jr., 4923 H Parkway 95823, both of Sacramento, Calif.

Filed Jan. 3, 1967, Ser. No. 5,281

Term of patent 14 years

(Cl. D23—10)

FIGURE 1 is a front elevational view of a water sprinkler hoop showing our new design, the rear being a mirror image of the front shown;

FIGURE 2 is an elevational view taken from one side thereof, the opposite side being essentially the same as the side shown;

FIGURE 3 is a cross sectional view to an enlarged scale taken on line 3—3 in FIGURE 1; and,

FIGURE 4 is a cross sectional view to an enlarged scale taken on line 4—4 in FIGURE 1.

We claim:

The ornamental design for a water sprinkler hoop, as shown and described.
